(57) CLAIM

The ornamental design for a toilet paper holder stand, as shown and described.

DESCRIPTION

FIG. 1 is a front perspective view of a toilet paper holder stand showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the figures representing rolls of toilet paper are provided for the purpose of illustrating an environment only and form no part of the claimed design.
